UNITED STATES PATENT OFFICE.

ROSS TAYLOR, OF NEW YORK, N. Y., ASSIGNOR TO AUTOMATIC VENTILATOR COMPANY, OF NEW YORK, N. Y., A CORPORATION OF NEW YORK.

WINDOW-VENTILATOR.

No. 884,052.

Specification of Letters Patent.

Patented April 7, 1908.

Application filed August 24, 1907. Serial No. 389,977.

To all whom it may concern:

Be it known that I, ROSS TAYLOR, a citizen of the United States, residing at New York city, in the county of New York and State of New York, have invented certain new and useful Improvements in Window-Ventilators; and I do hereby declare the following to be a full, clear, and exact description of the invention, such as will enable others skilled in the art to which it appertains to make and use the same.

My invention relates to certain new and useful improvements in ventilating devices for windows and more particularly for windows of sleeping and other railroad cars.

It has for its object to provide a portable and adjustable device by means of which a current of fresh air may under control be admitted to a room or car, and vitiated air ejected therefrom and consists of a panel adapted to be secured in place between the sill of a window and the lower rail of the sash, and provided with means for collecting and controlling an outside current of air and also ejecting interior vitiated air, and also in the details of construction all as will be hereinafter explained.

In order that those skilled in the art to which my invention appertains may know how to make the same, and that others may fully appreciate how to use and appreciate its advantages, I will proceed to describe its construction and the manner in which it may be applied to windows, referring by numerals to the accompanying drawing in which—

Figure 1 is a perspective view of the outside of one of my improved panel ventilators in position within the window of a sleeping car. Fig. 2 is a similar view showing the inside of the same. Fig. 3 is a horizontal section taken on the line *a*—*b* of Fig. 1. Fig. 4 is a horizontal section showing the device folded into compact form for ready transportation in an ordinary traveling bag or dress suit case. Fig. 5 is a vertical longitudinal section showing the manner in which the device may be adjusted to windows of varying width, and Fig. 6 is a cross-section taken on the line *c*—*d* of Fig. 1.

Similar reference numerals indicate like parts in the several figures of the drawing which represents the panel and its air controlling devices composed of sheet metal although as will be later explained I do not

wish to be confined to the use of any special material.

1, 1, represents a panel made of two sections hinged together at 2, in such manner that the inner end of a flat metal deflector 3, may be confined and held between the adjacent ends of the sections 1, 1, when they are locked or held in longitudinal alignment. Each section is provided with an air opening at a suitable distance from the locality of the outside deflector 3, which opening is preferably covered on the outside with wire gauze 4. Within the openings louvers 5 are arranged, and 6 are pivoted and adjustable controllers by means of which the currents of incoming and outgoing air can be regulated or entirely cut off.

When the device is made of sheet metal as shown, the ends of the interior controllers 6, are pivoted at their lower extremity and move in frictional contact with vertical stiffening braces 7, and between them and louver frame 7^a.

The adjacent hinged ends of the sections 1, 1, as well as the inner end of the outside deflector plate 3, are perforated to permit the passage of wire locking bolt 8, which is movable within keepers 9, as clearly seen at Fig. 2.

10, is a section longitudinally adjustable upon one of the main sections 1, of the panel in order that it may be readily adapted to windows of varying width.

The upper and lower edges of the panel as a whole are inclined to coincide with the surfaces of the sash and sill, and the outside deflector plate is likewise beveled for a similar purpose as clearly shown at Fig. 1.

I have shown section 10, rendered longitudinally adjustable upon one of the main sections 1, by means of vertical pins 11, passing through longitudinal slots in the upper and lower edges of the section 1; but any other suitable means for this purpose may be employed.

From the construction shown and described it will be readily seen that my improved ventilating device is adapted for use in any window and that the outside deflector 3, will arrest a current of air from either direction and deflect it into the adjacent opening in the panel and that such current is readily controlled by the inside controller 6, and that the other similar controller may be

2
adjusted so that the inside vitiated air is permitted to escape, which escape is facilitated by the vacuum existing at the rear of the outside deflector 3; this is more particularly the case when the device is used upon a railroad car for which it is more especially designed, and it will also be seen that the outside deflector plate 3, arrests cinders or smoke which as is well understood in car ventilation of the type involved, is free to descend by gravity, and ascend respectively, and thus prevented from entering the openings in the panel.

While I have designed my improved ventilating device with the view of providing an individual traveler with means for securing comfort in a day or sleeping coach, and have especially shown and described means by which the device is rendered portable and compact, it will be readily understood that the genius of my invention resides in a portable or removable ventilating device having an interior deflector for arresting a natural or induced current of air and directing it to the interior of an apartment and permitting the escape of interior vitiated air while at the same time providing means for controlling the ingoing and outgoing currents, or completely shutting them off.

30 It will be readily seen that when the devices are adapted for domestic habitations the dimensions may be such as to not only constitute means for arresting and controlling natural air currents but also to subserve 35 the purposes of ordinary window screens. It will also be readily understood that my improved ventilating device when designed as an ordinary equipment for railroad cars may be so proportioned and constructed as to fit 40 the windows thereof, in which case the extensible end section may be dispensed with.

I am aware that it is not new in principle to control the ingoing currents of fresh air and the outgoing currents of vitiated air by 45 means of an outside deflector located between two openings provided with interior controllers, for this generic idea constitutes the subject matter of Letters Patent No. 793,403, granted to me the 27th day of June, 50 1905, this generic principle however involves permanent and fixed position of the ventilating devices with reference to the apartment to be ventilated, and I am not aware that the principle referred to has ever been embodied 55 in a portable panel adapted to be removably secured in position between the sash and sill of a window or of such construction that it may constitute a traveling companion adapt-

ed for use where no similar means is provided by the railroad company. 60

The upper edge of the panel is preferably equipped with a strip of felting or rubber to constitute a dust-proof joint between the same and the sash.

Having described the construction and advantages of my improved ventilator what I claim as new, and desire to secure by Letters Patent is—

1. A panel ventilator adapted for location between the sill of a window and the lower rail of the sash, provided with an outwardly extending deflector plate located at the center thereof, and an opening each side of the deflector plate equipped with louvers, and having inside adjustable shields for directing and controlling incoming and outgoing air currents, substantially as hereinbefore set forth. 70

2. A panel ventilator for windows consisting of two sections each provided with an opening for the passage of air provided with louvers and inside adjustable shields for directing and controlling air currents, in combination with an exterior deflector plate hinged to the outer corner of one panel section and formed with an extension adapted to be confined between the adjacent ends of the two panel sections, substantially as and for the purpose set forth. 80

3. A panel ventilator for windows consisting of two sections each provided with air inlets and interior air current controllers said sections hinged together at their inner adjacent corners; an exterior deflecting plate hinged to the outer corner of the adjacent 95 end of one of the panel sections and formed with an extension adapted to be confined between the adjacent ends of the panel sections; and means for locking the said sections in aligned relation, substantially as and for the purpose set forth. 100

4. In a window ventilator composed of two panel sections provided with air inlets and interior air current adjustable controllers and an exterior deflector plate intermediate 105 the air inlets; a longitudinally adjustable section connected with the outer end of one of the main panel sections, substantially as and for the purpose set forth.

In testimony whereof, I have signed my name to this specification in the presence of two subscribing witnesses.

ROSS TAYLOR.
